UNITED STATES PATENT OFFICE.

RICHARD J. HOFFMEYER, OF LOWELL, ARIZONA.

AUTOMATIC DRAWER-COVER.

1,215,276.

Specification of Letters Patent.

Patented Feb. 6, 1917.

Application filed June 6, 1914. Serial No. 843,465.

To all whom it may concern:

Be it known that I, RICHARD J. HOFFMEYER, a citizen of the United States, residing at Lowell, in the county of Cochise and 5 State of Arizona, have invented new and useful Improvements in Automatic Drawer-Covers, of which the following is a specification.

This invention relates to improvements in 10 furniture, and more particularly to novel means for closing drawers and the like.

The leading feature of my invention consists in providing simple, inexpensive, and 15 highly efficient means whereby to automatically open and close the cover of a sliding drawer or the like.

A further object of my invention lies in 20 the provision of such a form of cover for a slideable drawer which possesses the important characteristics of locking itself in a 25 secure position relatively to the open end of the drawer when the latter is secured under the table, and which is adapted to yield before the advance of the drawer to open position in a simple and frictionless manner.

With the above and other objects in view 30 my invention consists in the combination, arrangement, and details of construction disclosed in the drawings and specification and then more particularly pointed out in 35 the present claim.

In the drawings wherein similar reference 40 characters designate similar parts throughout the respective views:—

Figure 1 is a longitudinal section view 45 showing the drawer cover in closed position,

Fig. 2 is a view similar to Fig. 1 showing 50 the drawer cover in open position, and

Fig. 3 is an end elevation of the device.

Referring to the drawings which are 55 merely illustrative of my invention the various details of construction are set forth. 1 designates a suitable drawer which may be of any desirable construction and is adapted to slide in a suitable table 9 in any suitable manner as by means of the longitudinally extending ribs mounted at the opposite sides of the drawer 1. These ribs are arranged to slide in the grooves 3 formed in the side plates 4 carried by the table or similar support. A cover for the drawer is designed to close the open end of the drawer effectively as by overlying the outer edges thereof in a manner to prevent the access into the drawer 55 of vermin or foreign particles.

It will be noted that the drawer 1 is of a

lesser length than the table and that it is formed with the downwardly inclined edges 5 at its open end extending from the top to the bottom thereof. The corners of the forward edges of said drawer are gradually and gracefully curved as at 5' for a purpose to be described. The drawer cover is designated 6 and is provided with a hinge 7 suitably secured upon the lower face of the 60 table 9. Said drawer cover is greater in length than the forward edges of the drawer whereupon it may rest at an inclination upon the part 7' of the bottom of the drawer, said cover being also provided with 70 a transversely extending beveled edge 8 so as to make smooth contact with said bottom 7' when in closed position. When the cover 6 makes engagement with the bottom of the drawer it will also make firm contact with 75 the inclined edges 5 thereof thereby effectively closing the drawer against the entrance of any foreign particles.

In operation the handle 10 which is mounted on the lower face of the forward 80 end 7' of the drawer may be grasped so as to cause said drawer to slide in the tracks or grooves 3 whereupon the rounded corners of the front of the drawer 5' will immediately engage with the obliquely disposed drawer cover 6 which extends transversely of said drawer, and said cover will bear upon and be forced upwardly as said drawer is slid longitudinally. Said drawer cover 6 will ride easily over the rounded corners of the drawer and when the latter shall have been moved outwardly from the table as is shown in Fig. 2 said cover will have been lifted to a substantially horizontal position swinging on its hinges 7, and fitting 85 in the space between the upper edges of the drawer and the lower face of the table as is clearly shown in Fig. 2. It will also be observed that when said drawer is slid into closed position the cover 6 will be free as soon as the rounded corners of the drawer pass under it to gradually move downwardly as far as the pitch or inclination of the outer edges of said drawer will permit. In other words instead of the cover dropping down 90 violently in the act of moving the drawer rearwardly to closed position the same will at all times rest upon the inclined edges 5 formed upon the drawer at its open end so as to move gradually into closed position as is shown in Fig. 1. Therefore the rounded corners 5' of the drawer serve as props for 95 100 105 110

supporting the cover when the latter is being lifted to open position as the drawer is slid forwardly.

From the above description the advantages flowing from the use of my invention will readily be discerned, and I do not limit myself to the exact details of construction herein disclosed except as falling within the purview of the appended claim.

10 What I desire to secure and claim by Letters Patent is:

In a cabinet, a drawer slidably mounted therein and having sides with rearwardly inclined front edges and rounded corners 5 at its upper plane, the bottom of the drawer extending beyond said sides, a closure pivoted at its upper end within the cabinet and normally disposed at an acute angle to rest

against said inclined edges for closing the drawer compartment, said closure being 20 elevated a distance approximately forty-five degrees to a full opened position by said inclined edges when the drawer is pulled out of the cabinet and supported by the upper edges of the drawer within the cabinet in its opened position, said closure being lowered by gravity as the drawer is retracted, and said rounded edges of the sides 25 permitting said closure to gradually assume its closed position.

In testimony whereof I affix my signature in presence of two witnesses.

RICHARD J. HOFFMEYER.
